FISHING TOOL

Crosby Gauthier, South Pasadena, Calif.

Application September 22, 1939, Serial No. 296,010

4 Claims. (Cl. 294—96)

This invention relates to oil-well fishing tools and has to do specifically with an improved pin-tap—which is a device designed for unscrewing and removing sections of drill pipe from a bore hole when the bit or other tool attached to the lower end thereof is stuck and cannot be dislodged—making it necessary to remove the attached drill pipe from the stuck bit or other tool, and remove it from the hole, in order to gain access to the stuck tool.

My object is to provide a pin-tap of more simple design than has heretofore been available and one which will operate more satisfactorily and reliably than any of its predecessors.

In the drawing which accompanies this specification:

Fig. 1 is an elevational view of my new pin-tap; Fig. 2 is a vertical sectional view; and Fig. 3 is a cross-sectional view along the line 3—3 of Figs. 1 and 2.

It is to be understood that each section of drill string which is to be unscrewed and removed from the hole has a box in its upper end and that the pin-tap is intended to be screwed into the box and then expanded so as to increase its frictional grip upon the box and thereafter rotated to the left—whereupon the drill string will part at one of its joints at a point below the pin-tap. And it will be further understood that the tool-string is provided with left-hand threaded tool joints which will not uncouple when the pin-tap is being rotated in a direction to unscrew the drill string.

In the drawing, reference numeral 1 identifies a sub at the lower end of the tool string—said sub being of reduced diameter at 2 to receive a sleeve 3 having a tapered external thread 4 designed to engage a box at the upper end of the drill string. Sleeve 3 is keyed or splined to the sub 1 so as to be rotatable therewith but slidable axially with respect thereto—three splines being shown in Fig. 3 and identified by numeral 5. Sleeve 3 is slotted through as at 6 to form three or more threaded segments whereby the threaded portion is rendered radially expansible.

A mandrel 7 connected to sub 1 is tapered at 7a and is operative in response to a relative upward movement to expand the threaded portion of the sleeve.

As an added precaution against loss of the sleeve and fish, in event of a breakage or detachment of the mandrel from the sub, a plurality of pins 8 may be inserted in the sub through elongated slots 9.

A jar should be inserted in the tool string above

the pin-tap—but since such jars are conventional equipment and well known, I do not consider it necessary to include the jar in the drawing.

The operation of my new pin-tap is very simple and self-evident. After the pin-tap has been screwed into the box, the tool string is lifted, which causes an upward movement of the mandrel 7 relatively to the sleeve. Due to the taper of the mandrel, the threaded portion of the sleeve 10 is expanded whereby to tightly grip the box. Then the tool string is rotated in a direction to unscrew the drill string—a joint of which will yield before the pin-tap thread will slip in the box. Repeated operations will remove the whole 15 drill string.

The function of the jar is to enable an upwardly directed blow to be applied to the mandrel for tightening the pin-tap in the box, and to enable a downward blow to be applied to the 20 mandrel for releasing the pin-tap at the derrick floor.

What is claimed is:

1. A pin-tap comprising a sleeve designed to be attached to the lower end of a tool string so as to be rotatable with said tool string and movable vertically relatively thereto, said sleeve having externally threaded expansible means for threading into the internal thread of a box, a tapered member supported by said tool string, said tapered member being coaxial with said sleeve and movable vertically with said tool string, both with said sleeve and relatively thereto, said tapered member being operative, when said expansible means is engaged with a box, to expand said expansible means in response to an upward movement of the tool string, and means for drivingly interconnecting said sleeve with the tool string for effecting rotation of said sleeve by the tool string, said means being operative to positively rotate the sleeve independently of frictional driving engagement between said tapered member and said sleeve.

2. A pin-tap comprising an annular sleeve member having an externally threaded portion designed to thread into and thus engage the internal thread of a box and split to permit expansion radially, said sleeve member being splined to the lower end of a tool string so as to be rotatable by and with the tool string and vertically movable relatively thereto, and a mandrel 50 co-axial with said sleeve member, said mandrel being attached to the lower end of the tool string and movable vertically with the tool string and relatively to said sleeve member, said mandrel having a tapered portion in engagement with the 55

split portion of said sleeve member and operative to effect a radial expansion of said split portion in response to an upward movement of said mandrel and tool string relatively to said sleeve member.

3. A pin-tap comprising externally threaded means designed to thread into and thus engage the internal thread of a box and consisting of a plurality of segments disposed about a common axis, each of which segments is capable of limited movement toward and away from said axis, said externally threaded means being designed to be connected to the lower end of a tool string and to be rotatable by and with said tool string and movable vertically, to a limited extent, relatively to said tool string and movable vertically, to a limited extent, relatively to said tool string, and actuating means carried by said tool string and movable vertically therewith, said actuating means being operative to effect a movement of said segments away from said axis in response to an upward movement of said tool string when said externally threaded means is restrained against upward movement.

4. A pin-tap comprising externally threaded means designed to thread into and thus engage the internal thread of a box and consisting of a plurality of segments disposed about a common axis, each of which segments is capable of limited movement toward and away from said axis, said externally threaded means being designed to be connected to the lower end of a tool string and to be rotatable by and with said tool string and movable vertically, to a limited extent, relatively to said tool string, and a mandrel co-axial with said externally threaded means, said mandrel being connected to said tool string and movable vertically therewith, said mandrel having a tapered portion in operating relation to said segments whereby to cause a movement of said segments away from said axis in response to an upward movement of said tool string when said externally threaded means is restrained against upward movement.

CROSBY GAUTHIER.
